UNITED STATES PATENT OFFICE

CHRISTOPH BECK, OF LUDWIGSHAFEN-ON-THE-RHINE, AND HEINRICH DIEKMANN, OF MANNHEIM, GERMANY, ASSIGNEES TO I. G. FARBENINDUSTRIE AKTIENGESELLSCHAFT, OF FRANKFORT-ON-THE-MAIN, GERMANY, A CORPORATION OF GERMANY

PROCESS FOR LIQUEFYING OXIDES OF NITROGEN

No Drawing. Application filed August 11, 1928, Serial No. 299,102, and in Germany August 18, 1927.

For many industrial processes, including for example the production of concentrated nitric acid from liquid nitrogen oxids, water and oxygen, a convenient direct method of liquefying the oxids of nitrogen without previous absorption by liquid or solid absorbents, is of the utmost importance. As the technical mixtures of oxids of nitrogen are often obtained highly diluted with other gases, the application of elevated pressure is for the most part inevitable, in order to obtain the vapor tension required for liquefaction, if it be desired to avoid having to deposit the nitrogen oxids in the solid form by an expensive process of cooling to extremely low temperatures, followed by thawing out into the liquid condition again.

We have now found that the oxids of nitrogen can be readily liquefied without difficulty, if the liquefaction be carried out in the presence of nitric acid. By the said addition of nitric acid the vapor tension of the liquid oxids of nitrogen consisting mainly of nitrogen tetroxid, together with a small proportion of nitrogen trioxid, to be liquefied is lowered. Consequently with even a small addition of nitric acid, far less cooling, or application of pressure, is needed than in the absence of such addition, in order to recover a given amount of liquid nitrogen oxids from a gaseous mixture with a given content of oxids of nitrogen, or in the case of undiluted nitrogen oxids the liquefaction may be effected by cooling alone. Small amounts of nitric acid for instance about 4 per cent calculated on the amount of nitrogen oxids to be separated are sufficient for the said purpose.

The said process may be carried out by adding nitric acid in proportion as the nitrogen oxids separate out from the mixture. Nitric acid may however also be provided, for example, in the condensing vessel, and this acid, after saturation with nitrogen oxids, gradually becomes completely dissolved in the layer of liquid nitrogen oxids first formed, so that, finally the condensed nitrogen oxids assume the condition of a homogeneous liquid containing a little nitric acid in solution. The nitric acid to be so added is preferably saturated with nitrogen oxids beforehand, as for

example by employing it for the absorption of the residual nitric oxid gases which have escaped condensation.

The nitric acid lowering the vapor tension may also be introduced, in the form of vapor, into the gaseous mixture prior to cooling to low temperatures so that it condenses, with the desired concentration, at the same time as the nitrogen oxids, and finally, such a degree of humidity and oxygen content may be imparted to the gaseous mixture of nitrogen oxids, which is to be cooled, that the desired amount of nitric acid is formed during the process of condensation itself. According to the purpose for which the liquefied nitrogen oxids are required, the concentration of the nitric acid therein may be arranged to be high or low, but in order to obtain the greatest possible reduction of the vapor tension, a high concentration of nitric acid approaching the saturation point is of special advantage.

The following example will further illustrate the nature of the said invention which however is not limited thereto.

Example

A dried gaseous mixture obtained by the combustion of ammonia and containing 190 milligrams of nitrogen oxids per liter, is compressed to 5 atmospheres and is passed through a cooling apparatus maintained at a temperature of -10° C. If 4 per cent of nitric acid be added to the liquefying nitrogen oxids, 54 per cent of the nitrogen oxids in the gaseous mixture will be recovered in the form of liquid nitrogen tetroxid, together with small amounts of nitrogen trioxid whereas without the addition of nitric acid, only 26 per cent of the nitrogen oxids will separate out.

What we claim is:

1. The process of liquefying nitrogen oxids which comprises cooling nitrogen oxids in the presence of small amounts of nitric acid.
2. The process of liquefying nitrogen oxids which comprises cooling and compressing gases containing nitrogen oxids in the presence of small amounts of nitric acid.
3. The process of liquefying nitrogen oxids

1,741,808

which comprises cooling and compressing gases containing in addition to the nitrogen oxides oxygen and water vapor in such quantities as to form a small amount of nitric acid in the process of liquefying and compressing the gases to the pressures as to the process of liquefying and compressing the gases to be 4. Which consists in cooling oxides in the presence of about 4 per cent of nitric acid to be liquefied.

6. Which containing nitrogen oxides in the presence of the amount of nitric acid to be liquefied. In testimony whereof we have hereunto set our hands.

CHRISTOPH BECK.
HEINRICH DIEKMANN.
